UNITED STATES PATENT OFFICE.

EMANUEL W. DUNN, OF LOS ANGELES, CALIFORNIA.

HEATER.

1,271,680.

Specification of Letters Patent. Patented July 9, 1918.

Application filed January 15, 1918. Serial No. 211,956.

To all whom it may concern:

Be it known that I, EMANUEL W. DUNN, a citizen of the United States, residing at Los Angeles, in the county of Los Angeles, 5 State of California, have invented new and useful Improvements in Heaters, of which the following is a specification.

This invention relates to heaters of various kinds and classes; and relates particularly to the provision of means in heaters, as hereinafter described, for increasing the effective radiation of heat therefrom by causing the heated gases of combustion to give up a large part of their heat before they 10 are discharged through the discharge stack, or otherwise discharged into the atmosphere. In providing a heater for heating a room, tent, or other inclosed space, or any open space, it is my object to provide a means for 15 delivering the pure heat units through the shell of the heater, increasing the radiation and conduction of heat from the heater, and for utilizing a large part of that heat which normally goes to waste because it is normally discharged by the heated gases of 20 combustion into the atmosphere. It is also an object of my invention to discharge the fumes and burnt gases from the heating member employed to the outside atmosphere 25 or at any desirable distant point.

In carrying my invention into actual practice, I provide various forms of heaters with my appliance. And it is an object of this invention to provide an appliance in such 30 form that it may be easily applied to various forms of heaters now in common use. To the draft body, stack or flue of a heater I apply a drum or other receptacle which is in effect an enlargement of the stack or flue, having 35 an enlarged heat radiating and heat conductive surface through which the heat of the gases within may be transferred to the surrounding air. This drum is, in effect, a member which receives the hot gases, holds 40 them, radiates and conducts their heat to the surrounding atmosphere, and then allows the gases to be carried off. From the drum a discharge stack may lead off to the atmosphere to discharge the fumes and 45 gases of combustion; but this final discharge stack is not a necessary adjunct of my invention. It will be understood that when I speak herein of a stack or flue, to which I apply my device, I mean to include within 50 that designation any kind of a passage or member within which the heated gases of combustion pass away from the flame. Such

a member may be the draftstack or flue of a heater, stove, or the like; the body of an oil heater; or any equivalent part through 60 which the heated gases pass.

With the foregoing described features in view, my invention will be best understood from the following detailed description of the application of my invention to various 65 forms of heaters; reference being had to the accompanying drawing in which specific, preferred and typical forms are illustrated.

In these drawings Figure 1 is an exterior elevation showing the application of my invention to a typical form of heater which has heretofore been largely used as an orchard heater and known as the "Dunn heater;" Fig. 2 is a vertical central section showing a preferred construction of my 75 device; Fig. 3 is a plan with parts broken away for purposes of illustration; Fig. 4 is a side elevation showing a different form of device; Fig. 5 is a front elevation showing the application of my invention to an 80 oil heater, commercially known as a "Perfection" oil heater; and Fig. 6 is an enlarged section showing a preferred construction of my device.

Referring first to Figs. 1, 2 and 3 of the 85 drawings, I show a heater comprising a liquid fuel receptacle or pot 10 into which air is admitted by a down draft tube 11 controlled by a damper at 12; auxiliary air being also admissible through a damper controlled opening at 13. The air admitted through the down draft tube passes out over the level of the liquid fuel 14 in pot 10 and sustains combustion above the fuel, thus generating a gas which is discharged into 90 the stack 15. The stack may preferably have air inlet openings as indicated at 31 controlled by damper 32 to admit air into the stack to perfect combustion therein; and the flame and heated gases of combustion rise 95 through the stack 15. This described form of heater is merely typical of a general class of heater; but for certain purposes, the combination of my invention with this particular kind of heater is very effective.

At the upper end of stack 15 I place the heat radiating drum 20. This drum is preferably made up in the manner indicated in the drawings, with a lower bell-shaped body 21 and an upper flat top 22. The body 21 has a central lower opening which registers with the opening in the stack 15; and a baffle 23 prevents direct flow of the heated gases of combustion from the stack 15 to the

final discharge stack 24. This final discharge stack 24 may rise directly from the back side of flat top 22, or it may lead out of the back part of body 21, as illustrated at 24^a in Fig. 4, leaving the top 22 unencumbered. Drum 20 is of sufficient capacity to hold a considerable volume of the heated gases of combustion. It is not limited to being of the relative size shown in the drawings. The heated gases of combustion remain for a longer time in the drum than they would in a continuous unenlarged stack, and radiate pure heat through the walls of the drum. The drum is preferably made in the shape shown so as to provide a relatively large radiating and conducting surface in proportion to its volume; and the upper surface or top 22 is made flat for the purpose of providing a place for cooking and warming operations.

The drum top 22 may be made with a peripheral flange 30 to provide strength and to provide a raised edge, if desired. Such a construction is particularly useful for cooking, etc. Fig. 6 shows the detailed structure of the drum. The lower part of body 21 may have a strengthening flange or ring 32'; and the nipple 33 may be shaped and connected with the body 21 and the flange 32 in the manner illustrated.

A heater such as herein described is capable of being used with any kind of fuel; and in practical use a low grade hydrocarbon fuel is used which develops a large amount of heat at a low cost. This heat, in the ordinary use of such a heater as an orchard heater, is delivered primarily to the atmosphere. But with my present invention a large proportion of this heat is radiated into the atmosphere surrounding the radiator drum, without being discharged through the gases of combustion into the atmosphere above. With my invention the radiating and conducting surface of such a heater may be increased many times. This particular form of my invention is most highly useful as a tent, hut, dug-out, or trench heater. It may also be used as a kitchen, parlor, or hot air furnace. It not only delivers heat at an exceptionally low cost, but it provides ample accommodation for cooking and warming food.

It will now be readily understood that my invention may be applied to various kinds of heaters, stoves, etc. In Fig. 5 I show the invention applied to a "Perfection" oil stove. The drum 20 in this case may be applied to the upper end of the flue ordinarily provided with the "Perfection" oil heater; or I may provide a special flue 40 provided with air inlet openings 41, air being admitted at this point to perfect combustion of the fuel. In such oil heat-

ers it is not usual to have a final discharge stack 24; and such a stack may or may not be used, as desired. However, it is always desirable to use a final discharge stack for the fumes and objectionable gases to be discharged out of the room into the open atmosphere.

The air used to promote combustion in the burner must be replaced by the admission of an additional air supply to the room.

It will be understood that the foregoing description of the application of my invention to a "Dunn" heater and a "Perfection" oil heater typifies the application of my invention to any and all kinds of heaters of that general classification. And it will now be understood how my invention may be applied to other forms of heaters, stoves and the like, without the necessity of further detailed explanation of those specific forms.

It will be understood that the office of the air inlet openings in the stack or body below the radiator drum is to admit air to complete combustion before the gases reach the drum, to develop the maximum heat and to eliminate soot, etc., and provide clean gases to go into the drum. The drum is thus kept clean and kept at its maximum conducting and radiating efficiency.

While I have described typical and specific applications of my invention in some detail, it will be understood that I do not thereby limit my invention to the particular embodiments herein set forth. Rather do I believe my invention to be broad in its nature; and accordingly I reserve to myself other similar applications of my invention, and any modifications or changes therein which may suggest themselves to those skilled in the art, or which may fall within the scope of the following claim.

Having described a preferred form of my invention, I claim:

A device of the class described comprising a liquid fuel receptacle providing a primary combustion chamber, a tubular stack for the receptacle having air inlet perforations therethrough within the zone of combustion and adapted for producing secondary combustion within the stack, a radiating drum communicating with the stack and adapted for receiving the heated gases of primary and secondary combustion from the stack and an outlet flue for the said drum.

In witness that I claim the foregoing I have hereunto subscribed my name this 8th day of January, 1917.

EMANUEL W. DUNN.
